UNITED STATES PATENT OFFICE.

NILS JOHAN JOHANSON, OF OCALA, FLORIDA, ASSIGNOR OF ONE-HALF TO
W. S. BULLOCK, OF SAME PLACE.

TRACE-CARRIER.

SPECIFICATION forming part of Letters Patent No. 427,422, dated May 6, 1890.

Application filed October 16, 1889. Serial No. 327,160. (No model.)

To all whom it may concern:

Be it known that I, NILS JOHAN JOHANSON, a citizen of the United States, residing at Ocala, in the county of Marion and State of Florida, have invented certain new and useful Improvements in Trace-Carriers for Plow-Harness; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 The special object of the invention is to combine the clasp or tongue-piece of a trace-carrier with its frame, so that said clasp may be easily put in or taken out, as hereinafter described.

20 Figure 1 of the drawings is a side elevation of my carrier with trace attached; Fig. 2, a detail perspective view of the frame of the clasp; Fig. 3, a similar view of the clasp, and Fig. 4 a similar view of the clasp and frame 25 with the former turned up.

In the drawings, A represents the frame provided with the upper slot a, lower slot a', intermediate plate a², and bearings or side pieces a³ a⁴. The latter have the holes a⁴ a⁴ 30 exactly opposite to each other for the purpose of receiving the clasp-trunnions b b', one of which is longer than the other to facilitate their insertion or removal.

The clasp B has on the rear bar b³, at the 35 under side thereof, the teeth b², which nearly touch the plate a² when the front bar b³ is

pressed down thereon. This causes the canvas or other fabric band to be tightly held in slots a a' and on the plate a². The teeth b² may be forwardly inclined on the bottom, or 40 the plate a² may gradually increase in thickness from bottom to top, so that the teeth of clasp may bite more forcibly on the canvas. Between the bars b³ b⁴ of the clasp is an opening for the finger for convenience in 45 taking hold of and lifting, as shown in Fig. 4 of the drawings.

D is the hook, on which is caught a link of the trace-chain E, so as to hold up the trace-chains when plowing, harrowing, or cultivat- 50 ing the soil.

The combined clasp, hook, and frame are preferably made of metal, so as to secure both the necessary strength and the greatest durability.

Having thus described all that is necessary to a full understanding of my invention, what I claim as new, and desire to protect by Letters Patent, is—

The combination, with the frame A, having 60 the hook D, slots a a', intermediate plate a², and side pieces a³ a⁴, having holes a⁴ a⁴, of the clasp or tongue piece B, having trunnions of unequal length to allow said clasp to be conveniently put in or taken out, as and for the 65 purpose described.

In testimony whereof I affix my signature in presence of two witnesses.

NILS JOHAN JOHANSON.
